(57) **CLAIM**

The ornamental design for a fold-up roller press, as shown and described.

DESCRIPTION

FIG. 1 is a perspective view showing the top, front and right side of a fold-up roller press which forms our new design, wherein the fold-up roller press is shown folded up; FIG. 2 is a perspective view showing the top, front and right side thereof, wherein the fold-up roller press is shown unfolded;

FIG. 3 is a rear elevational view thereof shown folded up; FIG. 4 is a rear elevational view thereof shown unfolded; FIG. 5 is a front elevational view thereof shown folded up; FIG. 6 is a front elevational view thereof shown unfolded; FIG. 7 is a top plan view thereof shown folded up; FIG. 8 is a top plan view thereof shown unfolded; FIG. 9 is a left side elevational view thereof shown folded up;

FIG. 10 is a left side elevational view thereof shown unfolded;

FIG. 11 is a right side elevational view thereof shown folded up; and,

FIG. 12 is a right side elevational view thereof shown unfolded.

The broken line portions of the figure drawings are included to show environment that forms no part of the claimed design.

1 Claim, 6 Drawing Sheets
